UNITED STATES PATENT OFFICE.

MELVIN L. STONE, OF LOWELL, MASSACHUSETTS, ASSIGNOR TO DRAPER COMPANY, OF HOPEDALE, MASSACHUSETTS, A CORPORATION OF MAINE.

AUTOMATIC WEFT-REPLENISHING LOOM.

No. 921,909.

Specification of Letters Patent.

Patented May 18, 1909.

Application filed April 1, 1904. Serial No. 201,069.

To all whom it may concern:

Be it known that I, MELVIN L. STONE, of Lowell, in the county of Middlesex and State of Massachusetts, have invented certain new and useful Improvements in Automatic Weft-Replenishing Looms, of which the following is a specification.

In operating with ordinary plain looms the main work of the weaver is in connection with the weft threads or filling. The warp threads are attended to outside of the weave room, being drawn in through the harness heddles, the reed spaces, the lease rods and the warp-stop detectors (if any), away from the loom, and being placed and arranged in the loom without any attention on the part of the weaver. Consequently, all that the weaver has to do in connection with the warp threads is to mend an occasional breakage. In the case of the weft, however, the conditions are substantially different, so much so that in the case of plain weaving the main duties of the weaver have been in connection with the supply of the weft. The weft has been prepared outside of the weave room only to the extent of winding it upon suitable bobbins, spindles or other carriers, and the entire work of placing the weft carriers in place to be used in the loom has fallen upon the weaver. The invention of the well-known Northrop loom (see U. S. Patents No. 454,810, June 23, 1891, and No. 529,940, Nov. 27, 1894) has largely diminished the duties of the weaver and enabled a single weaver to look after a much larger number of looms, since in the Northrop loom the weft or filling is automatically supplied to the running shuttle, thus avoiding cessation of the production of the loom and saving the weaver from the duties of removing the spent shuttle from the loom, replacing the spent weft-carrier in the shuttle with a fresh one, threading the shuttle, inserting the shuttle in the loom again, and restarting the loom. Even in the case, however, of the Northrop loom there is still left a large amount of work to be done to the loom in the weave room by an attendant in connection with the filling: The bobbins or other weft-carriers are brought in loose condition (ordinarily in a box) to the loom and have to be transferred by hand one by one into the battery hopper or magazine therefor, with which the loom is equipped. In addition to putting the bobbins or other carriers into the

battery it is necessary for the weaver to secure the weft ends to the weft stud or holder with which the battery is equipped, and in so doing care should be exercised to appropriately locate each thread as it extends from its bobbin to the weft stud or holder. The attention to these matters requires the larger portion of the weaver's time. In addition, the battery or magazine holds only a limited number of bobbins or other weft-carriers and in case all have been used before the weaver has an opportunity to replenish the battery the loom stops and ceases its production until it has been visited by the weaver, replenished with weft-carriers and again started. This cessation of production may continue for quite a period of time owing to the weaver being engaged, for example, in mending warp threads at another loom and the stoppage of one of the looms may not be immediately noticed. The necessity of looking after the filling supplied to the batteries is always upon the mind of the weaver and, consequently, interferes to an appreciable extent with the performance of other necessary duties.

The primary object of the present invention is to substantially take away the entire duty of the weaver with respect to the filling or weft and to have what is necessary in reference thereto done outside of the weave room, thus putting the management of the weft upon the same footing as that of the warp, and enabling a weaver to run a much larger number of looms. In achieving this object three principles have been introduced. In the first place, a readily detachable battery or magazine is employed which can be readily attached to and removed from the loom. This detachable magazine is of large capacity, capable of holding any desired number of weft-carriers, say one hundred or more, and readily capable of holding sufficient weft-carriers to run the loom for the entire day. This detachable magazine may be filled with weft-carriers outside of the weave room or away from the looms by employees whose sole duty may be to do so. These filled detachable magazines are preferably placed upon the looms before the weave room starts up for the day, and after the day is over all of the magazines are desirably removed from all of the looms irrespective of whether they are exhausted or not so that the looms are ready to receive replenished

105

110

magazines, then or the following morning, which have been refilled during the preceding day. Since the capacity of each magazine is sufficient for the running of the loom for the entire day, the weaver never has to consider the condition of the magazine, and the same should, under ordinary circumstances, never become exhausted. Of course, it is not essential that the detachable magazine should be used in this particular way, since it is feasible to wait until each magazine is entirely exhausted, in which event the loom will stop automatically and the magazine can be replaced with a filled one at any time that the organization and discipline of the mill render it expedient. In any event, however, the magazine is detachable from the loom, is filled with weft-carriers away from the looms or outside of the weave room, and holds a much larger supply than the batteries now employed on the Northrop loom. In the second place, means are employed for automatically feeding the weft-carriers from the detachable magazine when secured to the loom to the lay, whenever the weft in the running shuttle breaks or is exhausted, or whenever the weft approaches exhaustion, in case the weft detecting mechanism of the loom is of the kind which indicates a definite depletion, or the approaching exhaustion, of the filling, as in the case of the mechanism of the U. S. patent of George O. Draper, No. 527,014, Oct. 2, 1894. The weft-carriers can be automatically fed through a fixed chute, for a short distance and can then be transferred directly to the shuttle when a change of weft is called; or, the feeding from the detachable battery to the loom shuttles can be through the intermediary of the rotary battery already employed on the Northrop loom, such as is shown in U. S. Patents No. 529,940, Nov. 27, 1894, and No. 563,611, July 7, 1896. The feeding mechanism of the embodiment of the invention hereinafter illustrated and described in detail is of the latter type, that is to say, the weft-carriers are fed from the detachable magazine through a guide chute to the transerrer which transfers them to the lay; while the latter organization is shown as a modification. In the third place, special means are employed for taking care of the weft ends. In the Northrop loom it has been necessary not only to place the weft-carriers one by one by hand into the battery on the loom, but it has also been necessary to fasten the loose weft ends by hand to the weft stud or holder on the battery. This has been necessary in order that the shuttle may be threaded automatically when replenished with a fresh weft-carrier. In order that the weaver may be saved from this duty of securing the weft-ends, the weft-carriers are especially constructed. Each weft-carrier has a readily removable thread holder to which the weft-

end is secured before the weft-carriers are placed in the magazine. These readily detachable individual thread holders remain attached to the weft-carriers during their occupancy of the magazine. When, however, a weft-carrier is removed from the detachable magazine and is about to be transferred either directly to the shuttle or to the intermediate rotary battery, the detachable weft-end holder is automatically removed from its weft-carrier and is transferred to a position where it holds the weft-end in proper position to insure the automatic threading of the shuttle when the corresponding weft-carrier is inserted into the shuttle. In connection with these main principles, the embodiment of the invention in a loom involves many details which are of importance and which will be hereinafter called attention to in connection with the detailed description of one embodiment of the invention.

In order that the invention may be clearly understood, one embodiment thereof is illustrated in the accompanying drawings, in which:

Figure 1 is a front elevation of a mechanism showing the same attached to a loom, the upper portion of the detachable magazine being broken away. Fig. 2 is a vertical cross-section in the plane indicated by the line 2—2 in Fig. 1, looking in the direction of the arrow 1. Fig. 3 is a plan view of the bobbin feeding mechanism with the detachable battery removed. Fig. 4 is a vertical section in the plane indicated by the line 4—4 in Fig. 1, and looking in the direction of the arrow 4. Fig. 5 is a vertical cross-section also taken in the plane indicated by the line 2—2 of Fig. 1, but looking in the direction of the arrows 5. Fig. 6 is a section on the line 6—6 of Fig. 5. Fig. 7 is a vertical cross-section in the plane indicated by the line 4—4 of Fig. 1, looking in the direction of the arrow 7. Fig. 8 is a vertical longitudinal section taken in the plane indicated by the line 8—8 in Fig. 3. Fig. 9 is a plan view of the detachable magazine, with its bottom slide partly broken away. Fig. 10 is a vertical cross-section of the magazine in the plane indicated by the line 10—10 in Fig. 9. Fig. 11 is an enlarged front view of the mechanism for transferring the removable weft-end holders from the weft-carriers to the device which retains them until after the transfer of their weft-carriers to the shuttle has been completed. Fig. 12 is a section on an enlarged scale taken on the line 12—12 of Fig. 11.

In describing the embodiment of the invention shown in the drawings, reference will be made specifically to "bobbins" because they are the particular kind of weft-carrier which is illustrated, but it will be understood that any other form of weft-carrier can be employed. It will also be assumed that the loom is equipped with a weft-fork

which detects the absence of filling or weft so that the automatic transfer of a fresh bobbin to the shuttle takes place when the running weft breaks or is exhausted, but it will be understood that the invention is applicable to any automatic transfer irrespective of the way in which it is initiated.

The improved weft-carrier will be first described, reference being made to Fig. 9 of the drawings. A is a bobbin of well-known construction carrying a supply of filling or weft wound thereon. The bobbin, as illustrated, is of the construction shown in the U. S. patent to Northrop, No. 454,807, June 23, 1891, being equipped at its base with suitable provisions to enable it to be grasped and held by bobbin-holding jaws in the shuttle, such as are disclosed in said Northrop patent. The bobbin at its tip end is equipped with a readily detachable weft-end holder B. This holder is provided with a shank 25 which fits within a central longitudinal aperture (not shown) in the tip end of the bobbin. The head of the holder B is provided with suitable thread-holding grooves, as shown, to hold and retain the end of the weft thread. This weft-carrier is more fully set forth in Letters Patent of the United States No. 860,703, July 23, 1907. When the magazine is to be filled with bobbins one of these weft-end holders is put in place on each of the bobbins, and the end of the thread is put into one of the grooves in the holder and is gripped sufficiently to maintain it securely in place. The bobbins thus equipped are then placed in the magazine (to be hereinafter described) and, during the filling of the magazine, its transfer to the loom and the greater portion of the time which the bobbins occupy while on the loom, these detachable weft-end holders are maintained in place without any possibility of coming off from the bobbins accidentally or otherwise, and without any possible opportunity for the thread to become detached from its weft-end holder. As will hereinafter be set forth, at the appropriate time in the operation of the loom, the weft-end holder is automatically removed from the bobbin while still holding on to the end of the thread, so that the bobbin freed of the weft-end holder is then ready to be inserted into the running shuttle (just as in the case of the Northrop loom), while the removed weft-end holder retains its hold upon the thread so that the shuttle is automatically threaded in the same way as when the thread is held in the Northrop loom by the permanent weft-end holder with which the usual rotary battery is equipped.

The mechanism whereby the weft-end holders are automatically removed from the bobbins at the proper stage in the operation will be described after the magazine and its relation to the loom have been explained.

In the Northrop loom there is employed a starting shaft which is rocked in order to set in motion the filling or weft changing mechanism whenever there is a necessity for the replenishment of filling or weft in the running shuttle due either to the exhaustion, breakage, or approaching exhaustion of the weft in use. The effect of the movement of this starting shaft is to bring a transfferer into action, which transfers a fresh weft-carrier from the hopper battery or magazine into the shuttle on the lay, at the same time ejecting the spent weft-carrier from the shuttle. The organization and operation of this portion of the mechanism is now so well-known as to require no specific illustration and description, and is fully set forth in the Northrop patents already mentioned. It is with such mechanism that the present improvements are preferably employed and in the accompanying drawings only the transfferer C and dog X of this mechanism are shown. Concerning this transfferer C it is sufficient to say that it is held normally uplifted (as shown in Fig. 4) by a spring g (Fig. 1), and that it is moved downwardly (as shown in Fig. 12) to transfer a weft-carrier from the magazine in the shuttle and to eject the spent weft-carrier, and after the transfer has been made it is restored to its normal elevated position by said spring.

The usual rotary battery R of the Northrop loom is shown in Figs. 2 and 3. It is constructed and operated in the usual manner, except in particulars hereinafter specifically described.

The improved detachable magazine D is removably secured to the battery stand E above the battery. As hereinafter set forth, the loom has a fixed guide-chute K for the weft-carriers after the same have left the magazine D. This guide-chute is composed of two parts, the inner one of which is formed by a bracket F, integral with the battery-stand E, as shown in Figs. 1, 3 and 4, while the outer part is a part of a frame G, rigidly secured to the fixed stud H, upon which the transfferer swings; this frame G also furnishing an outer bearing for the rotary battery R, all as shown in Figs. 1, 7 and 11. The front end of the detachable magazine rests upon the two parts of the fixed guide-chute, as shown in Figs. 2, 4 and 8, while the body of the magazine rests upon a bracket I, extending up from the top of the stand E, as shown in Fig. 4. This bracket has a projecting tongue b and lateral shoulders c (see Fig. 4), while the magazine has fixed to its exterior a metal strap d, which embraces the tongue b and rests on the shoulders c. At its front the magazine has pins e which fit in sockets f, as shown in Figs. 2, 3 and 8. These connections hold the magazine accurately and securely in place on the loom, and at the

same time permit the ready and easy attachment and detachment of the magazine from the loom.

The magazine has side walls *h* and a permanent inclined bottom 28 (Figs. 9 and 10), upon which rest the stacks of groups of weft-carriers with which the magazine is supplied. The magazine has front and rear plates 29 and 30, and cross-partitions *l*, which divide it vertically into a plurality of channels, each adapted to receive and hold a vertical stack of weft-carriers. As shown in Fig. 9, it also has a vertical fore-and-aft partition 31 having a series of narrow vertical slots 32 for the necks 25 of the weft-end holders. The intermediate partitions *l* do not extend all the way down to the inclined permanent bottom 28 of the magazine, but terminate a sufficient distance thereabove to admit the passage therebeneath of a weft-carrier. The front channel of the magazine is temporarily closed at its bottom by a movable slide 33, which is closed when the magazine is not on the loom, and which is opened when the magazine is in place, as shown in Figs. 4 and 10. When the slide is thus drawn out, the front stack or group of weft-carriers in the magazine is in register with the short fixed guide-chute *K* which extends downwardly to a position opposite the front of the rotary battery *R*, as clearly shown in Figs. 3, 4, 8, 11 and 12. When the slide is withdrawn the front stack of weft-carriers drops down, filling the said guide-chute *K*, the bottom weft-carrier then resting upon fixed supports 34 (Fig. 8). The lowermost weft-carrier is retained in this position by yielding spring-fingers *q*¹ (Figs. 4 and 8) similar in construction and operation to the finger for supporting the tip of the bobbin set forth in U. S. patent of Stimpson, No. 664,790, Dec. 25, 1900, and such as is shown at *q* in Fig. 4 of the present drawings. In this instance, however, the spring-fingers *q*¹ stand vertically and are interposed at their free end between the lowermost weft-carrier and the adjacent portion of the rotary battery. The front or forward displacement of this lowermost weft-carrier is prevented by the coacting portions of a pusher *S* (Fig. 4), the office of which is to automatically transfer at the appropriate time the lowermost weft-carrier from the guide-chute into the rotary battery. This pusher is equipped with appropriate parts 35 and 36 which act respectively upon the head and tip of the weft-carrier during the transfer into the battery, and they correspond in construction with corresponding parts of the usual transerrer of the Northrop loom. This pusher is secured to the transerrer *C* so as to operate in unison therewith. When the transerrer *C* acts to transfer a weft-carrier from the battery into the lay, the pusher simultaneously acts to transfer a weft-carrier into the battery, so that the

battery is kept supplied with a uniform number of weft-carriers so long as the magazine and guide-chute furnish weft-carriers. The pusher is provided with a suitable retainer *L* which passes under the front stack of shuttles during the transferring movement and the return therefrom so as to uphold the front stack of weft-carriers during this period.

When the front stack of weft-carriers in the detachable magazine has been exhausted through successive transfers of the weft-carriers composing the same into the rotary battery, the second stack of weft-carriers comes into play, dropping down by gravity as fast as needed. The weft-carriers of this second stack roll down (as occasion requires) the inclined fixed bottom 28 to the open bottom-throat of the magazine, and thence into the fixed guide-chute, and during this movement they pass underneath the first partition. This action continues until this stack is exhausted, and then the third stack comes into action, and so on, until all of the stacks have been exhausted. It is obvious that the magazine can be made of a height to accommodate any desired number of weft-carriers, and it is desirable that the capacity of the magazine should at least be sufficient to keep the loom running for an entire day. The drawings show the top of the magazine broken off to indicate that it may be of any desired height.

To facilitate the proper descent by gravity of the weft-carriers of the several stacks without interfering with each other, appropriate means, such as automatic gates 37 at the bottom of each partition *l*, are employed. These gates normally occupy their depending vertical positions shown in Fig. 4, where they prevent the premature rolling down of the bottom weft-carriers of each stack which is not in communication for the time being with the guide-chute. Each of these gates is carried upon a horizontal shaft 38 journaled beneath the corresponding partition *l*, and it extends out through the inner wall of the magazine where it has a projecting arm 39. This arm is normally held in a vertical position by means of a swinging latch 40, which is also exterior to the rear wall of the magazine and is mounted upon a horizontal shaft 41 extending parallel with the shaft 38. This latch is lifted by means of a lifting spring 42, but the latch is held normally down against the tension of said spring by means of the weft-carriers in the corresponding channel which bear against depending arms 43 (see Figs. 8 and 9). As long as there are weft-carriers in the corresponding channel extending above the plane of the bottom of the corresponding partition *l* said carriers are in contact with said arms 43 and by their weight overcome the tension of the spring 42, and thereby maintain the latch 40 down,

holding the next succeeding gate 37 locked in its vertical weft-carrier-restraining position, as clearly shown in Fig. 10. When, however, the weft-carriers in an advance 5 channel fall below the lower ends of the arms 43 then the spring 42 throws the latch 40 up, thereby unlocking the gate 37, which has previously restrained the weft-carriers in the channel next in the rear, thus bringing said 10 weft-carriers into coöperative relation with the stationary chute K. Hence, at the proper time and in the proper succession, the different stacks or groups of weft-carriers in the different channels of the magazine are 15 brought into action. When the magazine is again filled with weft-carriers these latches and gates are re-set by hand.

As each weft-carrier at the bottom of the stationary guide-chute K is transferred into 20 the rotary battery R, and as the lowermost weft-carrier in said battery is transferred into the running shuttle (which operation is indicated in Fig. 12) the rotary battery is immediately thereafter rotated in the direction 25 indicated by the arrow 44 in Figs. 4 and 12, in the customary manner of the Northrop loom and by the customary mechanism for this purpose with which said loom is equipped. This leaves the spring-finger q¹ 30 free to return from its displaced position, shown in Fig. 12, to its normal position, shown in Fig. 4, where it holds the next descended weft-carrier in proper position. In this embodiment of the invention a mechanism 35 for ejecting and displacing the weft-end holders from the weft-carriers is employed. A specific mechanism for this purpose is illustrated in the drawings. The rotary battery is not provided with the usual weft-holding 40 wheel rotating with the battery, as in the usual construction of the Northrop loom, but instead it coöperates with a receiver and conveyer for the ejected and displaced weft-end holders B. This receiver and conveyer comprises 45 a stationary casing T which is circular in form and concentric with the axis of the rotary battery. The rotating shaft 45 of the rotary battery extends outwardly beyond its outer end (as clearly shown in Figs. 1 and 3), 50 and extends into and is journaled in said stationary casing T. Fast to and rotating with this shaft 45 is a rotary plate U (see Figs. 5 and 6) which carries a horizontal circular or drum-like flange 46 from which extend radially 55 a series of blades 47 corresponding in number and position with the several weft-carrier retainers (of the usual kind) with which the rotary battery is equipped. There is thus formed within the casing a series of 60 pockets V corresponding in number with the number of weft-carriers which the rotary battery (if entirely filled) would be capable of holding. It is, therefore, obvious that if a weft-end holder were ejected into one of these 65 pockets, it would be carried around in con-

sonance with the movement of the battery as the shaft 45 and plate U rotate, thus maintaining a definite relation throughout the rotation of the battery between the weft-carrier inserted into the battery and the corresponding weft-end holder which had been displaced therefrom. On reference to Figs. 5 and 6, it will be noted that a circular gap 48 is left between the rotary plate U and the stationary casing T which permits the free 75 passage of the thread extending from the weft-carrier in the rotating battery to its corresponding weft-end holder located in the rotating pocket. As the result of this construction and arrangement, the weft-end 80 holder is brought to the proper position when its corresponding weft-carrier is to be transferred from the rotary battery into the running shuttle, so that the running shuttle will be automatically threaded (in the usual 85 manner) when said corresponding weft-carrier is inserted into the shuttle. After the automatic threading has been thus accomplished, the corresponding weft-end holder, which has then accomplished its function, is 90 (owing to the continued rotation of its pocket) discharged through an opening 49 (see Fig. 1) near the bottom of the stationary casing.

It only remains to be explained how each 95 weft-end holder B is in turn displaced from its weft-carrier and ejected into its proper pocket of the rotary weft-end holder receiver. This is accomplished by a displacer N. As shown in Figs. 1 and 8, this displacer 100 N is mounted to slide horizontally upon a fixed horizontal rod 50, and it performs its outward or ejecting stroke under the action of a propelling spring P. Fig. 1 shows the displacer after it has performed its propelling 105 office, and this is its normal position. Fig. 11 shows it in its inward position where it is temporarily held by a pivoted spring-latch 12, shown best in Fig. 3. When the displacer thus occupies its inner position with 110 an open-mouthed slot m, a lip 51, is within the head of the then lowermost weft-end holder B, as shown in dotted lines in Fig. 8. When in this position the neck 25 of the holder B occupies the slot m. By releasing 115 this spring latch 12 from the displacer, the propelling spring P moves the displacer quickly outwardly, carrying with it the weft-end holder B, and forcibly ejecting it through a fixed tube W which directs it to one of the 120 pockets V in the rotary weft-end holder receiver and conveyer. This tube W has an open-thread slot 52 at the rear, as best shown in Fig. 8, which permits the free passage of the thread therefrom as the rotary 125 battery rotates. As the weft-end holder is shot through this tube W the thread reels off from the weft-carrier with it so that the thread remains intact. The displacer is thus released and is again thrust inwardly to 130

put its propelling spring again under tension by appropriate automatic mechanism which operates with the transferring mechanism. The displacer is immediately acted upon to 5 be pushed inward so as to put its propelling spring under tension by means of a lever 53 (see Figs. 1 and 11), which is pivoted at 54 to a stationary part of the loom. The outer and lower end of this lever is pivotally connected to an intermediate lever 55 (best shown in Figs. 11 and 12), which is pivoted at 56 to a stationary part of the loom. The lower end of this lever 55 has pivoted to it a slotted link 57 and through this slot extends 10 a rod 58 which is secured rigidly to the usual lower arm 59 of the transerrer C. When the transerrer is swung downwardly from the position shown in Fig. 4 to the position shown in Fig. 12 for the purpose of inserting 15 a fresh weft-carrier into the running shuttle, it carries the rod 58 forwardly with it, thus swinging the intermediate levers 55 and 53 on their pivots and thereby the displacer is moved inwardly until it is automatically 20 locked by the spring-latch 12 (see Figs. 3 and 11), this also putting the propelling spring P under tension. The displacer is thus brought into position so that when the stack of weft-carriers falls by gravity, the head of 25 the weft-end holder will be outside of the lip 51 of the displacer, with its neck in the slot m. Immediately after the stack of weft-carriers has descended, the displacer is tripped so as to be shot outwardly by its propelling 30 spring, whereby the weft-end holder of the then lowest weft-carrier is displaced and ejected into the corresponding pocket of the rotary receptacle for the weft-end holder. This tripping of the displacer is effected 35 through intervening instrumentalities when the transerrer C is restored to its normal position. As shown, the lower arm 59 of the transerrer has pivoted to it the usual dog X which is commonly employed in the 40 Northrop loom and which is illustrated, for example, in the Stimpson patent No. 664,790, Dec. 25, 1900. When the transerrer resumes its normal elevated position a stud 60 on said dog comes in contact with the lower 45 end of a lever 61 which is pivoted at 62 to a stationary part of the loom (see Figs. 1, 2 and 4). The upper end of this lever coöperates with a crank arm 63 of a horizontal rock-shaft 64, suitably journaled to a fixed 50 part of the loom (see Fig. 1) and the outer end of this rock-shaft has a depending crank arm 65 which coöperates with the tail end of the spring-latch 12. As a consequence, when the dog X is returned to its normal position, the lever 61 and the rock-shaft 64 are appropriately moved to swing the latch 12 and to thereby release the displacer.

The entire operation of this embodiment of the invention is as follows: The weft-carriers are supplied with weft-end hold-

ers and the ends of the threads are secured at any suitable place and at any convenient time by an unskilled attendant. The detached magazine is then filled with the weft-carriers with their attached weft-end 70 holders, during which time the bottom slide 33 is closed. The magazine is or may be of sufficient capacity to hold sufficient weft-carriers to run the loom for an entire day. The filled magazine is then taken to the 75 loom and is put in place and the slide 33 is opened, so that the front stack or group of weft-carriers in the magazine is then in register with the fixed chute K and the weft-carriers drop down by gravity until the 80 stack is supported by the fixed supports 34. If this is the initial starting of the loom the weft-end holder of the lowermost weft-carrier is removed by hand and placed in the corresponding pocket of the rotary receiver 85 and conveyer. Also, if this is the first starting of the loom the rotary battery R is filled with weft-carriers by hand and the weft-holders therefor are either placed in proper pockets in the rotary receptacle or the weft 90 ends may be simply attached to the shaft 45 in the manner common to the Northrop loom. These hand operations will not be necessary after the loom has been once set in operation. When the weft in the running shuttle requires replenishment the starting mechanism with which the loom is equipped acts automatically in the manner usual to the Northrop loom, and thereupon the transerrer operates to transfer the 100 lowermost weft-carrier in the rotary battery into the running shuttle. Simultaneously, the pusher S acts to transfer the lowermost weft-carrier in the chute K into the rotary battery. This same movement of the transerrer 105 sets the displacer N. The transerrer then rises, the front stack of weft-carriers drops down one place, the rotary battery is rotated forwardly one step, and the displacer is released, thereby removing the 110 weft-end holder of the lowermost weft-carrier in the fixed chute K and ejecting it into the appropriate pocket of the rotary weft-end holder receiver. The rotary weft-end 115 holder receiver rotates with the battery R so that the removed weft-end holder occupies the proper relation relatively to its weft-carrier until after the weft-carrier has been transferred into the shuttle-box on the lay, thereby insuring the automatic threading of 120 the shuttle. After this has been accomplished the then functionless weft-end holder is automatically discharged from the rotary weft-end holder receiver. This operation continues until the first stack of weft-carriers in the detachable magazine is substantially exhausted, whereupon the retaining gate for the second stack of weft-carriers in said magazine is automatically opened and the second stack is thus brought into opera- 125 130

tive communication with the fixed guide chute. When the second stack of weft-carriers in the magazine is exhausted, the third stack is brought into operation and so on until all of the weft-carriers in the magazine are exhausted. In case there should be no attention to the magazine when empty, the loom will continue running until not only is the magazine empty, but the rotary battery as well, and thereafter the loom will be automatically stopped just as in the Northrop loom after the rotary battery thereof has been exhausted. When the transfer of a weft-carrier to the lay takes place its weft-end holder is detached but still retains its hold upon the thread. This detached holder affords a yielding resistance to the thread so that there is no sudden shock upon the thread due to its transfer to the lay and its first flight through the shed such as is incident to the arrangement in the well-known Northrop loom wherein the thread is secured to a fixed thread-holder. This yielding character of the weft-end holder (which it possesses when the transfer takes place) is of importance since it eliminates a large portion of the weft-breakage which has heretofore occurred at the time of transfer.

It is obvious that many changes may be made without departing from the spirit and principle of this invention. For example, although the greatest advantage of the present invention would be secured by making the magazine readily detachable, nevertheless it is obvious that some of the advantages of the present invention could be secured by permanently securing the magazine to its supporting stand. While such permanence would necessitate the filling of the magazine at the loom, nevertheless this would have to be done only at remote intervals as compared with the attention to the battery of the Northrop loom, and could be done out of hours so as not to interfere with the work of the weaver.

An embodiment of the general principles of my invention is set forth in the companion application of William S. Southwick, of the town of Hopedale, in the county of Worcester and State of Massachusetts filed April 1, 1904, Serial No. 201,054. I do not claim any of the specific features invented by this party, but his improvements serve to embody the principles of my invention, serve to illustrate the same, and are within the intended scope of my principal claims.

I have herein shown an improved weft-carrier with my detachable weft-end holder adapted thereto. I do not make any claim to this invention in this application because it constitutes the subject-matter of said patent No. 860,703.

I claim as my invention:—

1. An automatic weft-replenishing loom

having, in combination, a detachable magazine, a fixed guide-chute in communication with said magazine, a rotary battery, a pusher for transferring weft-carriers from said guide-chute into said rotary battery, and a transfer for transferring weft-carriers from said rotary battery into the running shuttle.

2. An automatic weft-replenishing loom having a rotary battery, an automatic transfer for co-operating therewith, a detachable magazine, and an automatic pusher for transferring weft-carriers from the said magazine to the said rotary battery.

3. An automatic weft-replenishing loom having, in combination, a detachable magazine provided with means for holding a plurality of groups of weft-carriers, a transfer, and means for automatically bringing into co-operation with the said transfer each of the said groups of weft-carriers in succession.

4. An automatic weft-replenishing loom having, in combination, a readily detachable magazine provided with means for holding a plurality of weft-carriers, a transfer, and means for automatically bringing the weft-carriers of said magazine one by one into co-operation with said transfer.

5. An automatic weft-replenishing loom having a readily detachable magazine adapted to hold a plurality of groups of weft-carriers.

6. An automatic weft-replenishing loom having, in combination, a detachable magazine, an automatic transfer, and means for feeding the weft-carriers from the detachable magazine when secured to the loom to the transfer.

7. An automatic weft-replenishing loom having a readily detachable magazine adapted to hold a plurality of weft-carriers.

8. An automatic weft-replenishing loom having, in combination, a rotary battery independent of the lay for holding weft-carriers and from which said carriers are supplied to the loom, and automatic mechanism for supplying weft-carriers to said rotary battery.

9. An automatic weft-replenishing loom having, in combination, means for maintaining in place a weft-carrier having a detachable weft-end holder, a step-by-step rotating weft-end holder receiver having a plurality of weft-end holder receiving pockets, and automatic means for removing the weft-end holder from the weft carrier and transferring it into the appropriate pocket of said rotary receiver.

10. An automatic weft-replenishing loom having, in combination, means for sustaining a weft-carrier with a detachable weft-end holder, automatic means for displacing the weft-end holder from the weft-carrier, and an automatic transfer for transferring into the lay the weft-carrier after the weft-end holder has been displaced therefrom.

11. An automatic weft-replenishing loom having, in combination, means for sustaining a weft-carrier with a detachable weft-end holder, and means for automatically displacing said weft-end holder. 50
12. An automatic weft-replenishing loom having, in combination, means for maintaining in place a weft-carrier with a detachable weft-end holder, and an automatic spring-10 propelled displacer for removing said weft-end holder from said weft-carrier.
13. A weft-carrier holding magazine for an automatic weft-replenishing loom having a movable slide which retains weft-carriers 15 in place therein when the magazine is remote from the loom.
14. The combination of means for arranging a plurality of weft-carriers in order apart from the loom, means for fitting said arranged weft-carriers to the loom, and means for automatically bringing said weft-carriers successively into weaving action. 65
15. An automatic weft-replenishing loom having, in combination, means for holding 25 and feeding a plurality of weft-carriers, and a separate yielding holder for the end of the thread of each weft-carrier.
16. An automatic weft-replenishing loom having a stationary magazine containing a 30 plurality of stacks of spare weft-carriers, a single guide-chute communicating with said several stacks, and a movable gate which cuts off one stack from said guide-chute when another stack is in communication 35 therewith.
17. An automatic weft-replenishing loom having a magazine containing a plurality of stacks of spare weft-carriers, a common guide-chute communicating with all of said 40 stacks, and movable gates between said stacks and said guide-chute.
18. An automatic weft-replenishing loom having a magazine provided with a plurality of channels for spare weft-carriers, said weft-45 carriers moving in said channels by gravity, and separate retaining means at the lower end of each of said channels to retain the weft-carriers.
19. In a weft replenishing loom, a magazine, having two or more compartments or 50 guide-ways for weft carriers, and rigidly secured in a fixed position, and having a discharging end common to all the compartments, and means for yieldingly holding a weft carrier at said end. 55
20. In a weft replenishing loom, a magazine, having two or more compartments or guide-ways for weft carriers, and rigidly secured in a fixed position, and having a discharging end common to all the compartments, and means for yieldingly holding a weft carrier at said end, and in a position to be engaged by the transfer of the transerrer mechanism. 60
21. In a weft replenishing loom, a magazine having two or more compartments or guide-ways for weft carriers, and rigidly secured in a fixed position, and having means for guiding the lowest weft carrier in each compartment to the discharging end of the magazine, and means for yieldingly holding a weft carrier at said end. 65
22. In a weft replenishing loom, the combination with a stationary magazine having two or more compartments for weft carriers 70 and a discharging end common to all the compartments, of mechanism for each compartment to retain the weft carriers in each compartment, and to release the lowest weft carrier in a compartment to allow its passage to the discharging end of the magazine. 75
23. In a weft replenishing loom having a stationary magazine with a plurality of compartments for weft carriers, separate means to retain the weft carriers in each of said compartments, and means to release the lowest weft carrier in each compartment. 80
24. In a weft replenishing loom, a magazine having a plurality of compartments for weft carriers, and a chute from each compartment to a common position at the discharging end of the magazine. 85
25. In a weft replenishing loom, a stationary magazine having compartments for weft carriers, open from top to bottom, movable 90 means for each compartment to retain the superposed weft carriers therein, and means to release the lowest one of one set of weft carriers, and allow it to be moved into a position to be transferred. 95
26. In a weft replenishing loom, a stationary magazine having a plurality of compartments, each compartment for a series of weft carriers, a chute from each compartment to guide a weft carrier into a common position. 100
